UNITED STATES PATENT OFFICE.

ARTHUR H. TREULIEB, OF AMSTERDAM, NEW YORK.

WARDROBE BAG.

Application filed November 12, 1923. Serial No. 674,152.

To all whom it may concern:

Be it known that I, ARTHUR H. TREULIEB, a citizen of the United States, residing at Amsterdam, in the county of Montgomery and State of New York, have invented new and useful Improvements in Wardrobe Bags, of which the following is a specification.

Reference may be had to the accompanying drawings, and the reference characters 10 marked thereon, which form a part of this specification. Similar characters refer to similar parts in the several figures therein.

This invention relates to wardrobe bags adapted to support and protect garments 15 from dust, moth and the like.

The principal object of the invention is to provide a dust-proof and moth-proof bag of this character within which the garments can be hung in proper form, and the interior of which is readily accessible for the 20 insertion and removal of the garments.

Other objects will appear in connection with the following description.

Fig. 1 of the drawings is a view in front 25 elevation partly broken away and shown in section of a wardrobe bag embodying my invention.

Fig. 2 is a side elevation of the same partly broken away and shown in section.

Fig. 3 is a horizontal section of the same 30 taken on the broken line 3—3 in Fig. 1.

Fig. 4 is a similar section partly broken away taken on the broken line 4—4 in Fig. 1.

Referring to the drawings wherein the invention is shown in preferred form, 1 is an 35 envelope which is closed except for a side opening, 2.

The envelope may be formed in any known manner of flexible material, but is preferably 40 formed of a width from side to side sufficient to freely receive garments of usual width, and of a depth from front to back to freely receive one or more garment-supporting hangers with garments thereon.

45 The edges of the envelope bordering the opening, 2, are formed with beads, 3, and the opening is adapted to be securely closed by means of a split tube or tubes, 4, adapted to closely embrace and hold together the oppositely disposed beaded edges, 3, as shown in Fig. 4.

If desired, a plurality of said tubes, 4, may be employed as shown in Fig. 1.

The tubes, 4, are applied to and removed from the beaded edges, 3, by sliding the 55 tubes up or down along said edges.

Within the upper end of the envelope is a frame holding said upper end expanded. This frame preferably includes a middle longitudinal bar, 5, and two separated side 60 bars, 6 and 7, connected with the middle bar, 5, at intervals by bows, 8.

The bag is supported by means of an exterior hanger, 9, connected with the middle bar, 5, of the enclosed envelope-expanding 65 frame. Any other exterior supporting means connected with the bar, 5, may be used in place of the strap or hanger, 9, if desired.

At about the middle of the enclosed envelope-expanding frame, the side bars, 6 and 7, are connected together by a cross-bar, 10, adapted to receive one or more garment-supporting hangers, 13.

In use the bag is supported by engaging 75 the strap, 9, with a hook or other suitable support from which the bag is suspended.

The side of the bag having the opening, 2, is then opened by sliding the tube or tubes, 4, up or down to free them from the 80 beaded edges, 3.

A garment, 12, supported upon a garment-hanger, 13, is then inserted through the opening, 2, and the hook, 14, of the hanger, is engaged with the cross-bar, 10, of the envelope-expanding frame.

By sliding the hanger, 13, along the rod, 10, other garment-supporting hangers can be similarly inserted within the envelope and supported from the same cross-bar.

After the desired garment-supporting hangers have been thus inserted, the opening, 2, is closed by bringing its beaded edges together and sliding over them the tube or tubes, 4.

What I claim as new and desire to secure by Letters Patent is—

1. A wardrobe bag having a flexible envelope closed except for a side opening, a frame for holding the upper end of the envelope expanded, said frame including a rigid middle longitudinal bar and two sepa-

rated rigid longitudinal side bars on a lower plane than, and connected with, said middle bar; a rigid clothes-hanger-receiving cross-bar connecting together said side bars, and 5 exterior bag-supporting means connected with said middle bar.

2. A wardrobe bag having a flexible envelope closed except for a side opening, a frame for holding the envelope expanded, 10 said frame having means for supporting a clothes-hanger and including a rigid middle

longitudinal bar and two separated longitudinal side bars on a lower plane than said middle bar, arched braces connecting together at intervals said middle bar and the 15 respective side bars, and exterior bag-supporting means connected with said middle bar.

In testimony whereof, I have hereunto set my hand this 9th day of November, 1923.

ARTHUR H. TREULIEB.
